UNITED STATES PATENT OFFICE.

FRANK L. CUNNINGHAM, OF MONTREAL, QUEBEC, CANADA.

MOP.

1,160,265.

Specification of Letters Patent.

Patented Nov. 16, 1915.

Application filed March 29, 1915. Serial No. 17,904.

To all whom it may concern:

Be it known that I, FRANK L. CUNNINGHAM, a citizen of the Dominion of Canada, and resident of the city of Montreal, in the 5 Province of Quebec and Dominion of Canada, have invented certain new and useful Improvements in Mops, of which the following is a full, clear, and exact description.

10 This invention relates to improvements in mops, and the object of the invention is to provide a means whereby water may be squeezed out of the mop, without the necessity of wetting the hands, by a simple operation of the mop holder.

15 A further object is to provide a device which will operate by a simple back and forward movement of the handle, without the necessity of manipulating additional parts.

20 The device consists essentially of a handle carrying a mop cloth, and a frame slidably mounted on the handle carrying a pair of rollers arranged to squeeze out water from 25 the cloth. An automatically operating device for controlling the rollers is also provided.

25 I am well aware that a number of mops have been devised having rollers carried by 30 frames mounted on the handle, such devices having additional manually operable means for separating and closing the rollers. The chief improvement over such devices embodied in the present invention is that the 35 opening and closing of the rollers is accomplished automatically.

35 In the drawings which illustrate the invention:—Figure 1 is a side elevation of the device. Fig. 2 is a plan view. Fig. 3 is a 40 side elevation showing the position of parts at the moment of complete wringing. Fig. 4 is a view similar to Fig. 2 showing the rollers separated for the re-introduction of the dry mop cloth. Fig. 5 is an enlarged 45 detail of the operating staple.

Referring more particularly to the drawings, 11 designates a handle having at one end any suitable means 12 holding a mop cloth 13. A ferrule 14 is slidably mounted 50 on the handle and carries a pair of frame members 15 extending from the ferrule at right angles to the handle, and then bent to extend parallel with the handle at a suitable distance therefrom. These frame members 55 are provided at suitable intervals with apertures, and at the ends adjacent the mop

cloth are connected by a transverse member 16. A second frame member 17 of substantially U-shape is provided having its ends pivoted at 18 to the side frame members 15. 60 The side frame members 15 and the member 17 each carry between them transversely disposed rollers 19 and 20 respectively, mounted by means of pins 21. It will be seen in Figs. 1 and 3 that the members 15 and 17 are 65 diverged slightly from their pivotal connection point 18, so that the rollers 19 will normally embrace the mop holder 12. A bridle 22 is slidably mounted on these members, and it will be readily seen that by 70 sliding the bridle back and forth on the diverging members that the rollers may be pressed toward one another or allowed to separate. This bridle is connected to a rod 23 which passes along under the handle 75 parallel therewith, and terminates in a ring 24 surrounding the handle a suitable distance from the ferrule. A staple 25 is provided on the handle embracing the rod 23 normally in substantial contact with the 80 bridle, as shown in Fig. 1.

The device may be conveniently constructed of heavy wire, as shown in the drawings, in which case bearings for the pivotal connection of the jaw member 17 85 and for the rollers 19 and 20 may be easily formed by looping the wire, as clearly shown at 26.

In order to hold the rollers apart until the mop is reinserted, a link 28 is pivotally 90 mounted on one end of the bridle 22, and slidably embraces one side of the frame 17. When the bridle is drawn back to release the frame, the link has the effect of pulling the jaw down and holds the jaw against shutting, until the mop is completely reinserted 95 between the rollers and the staple 25 strikes the bridle and drive it forward.

It is obvious that all mop cloths are not of the same thickness, and if the rollers are held 100 a fixed distance apart, a thick cloth will be wrung much drier than a thin one. To overcome this disadvantage, the staple 25 is located on the handle to engage the bridle and close the rollers sufficiently for wringing a 105 cloth of ordinary thickness. A small filler 29 of hook shape is pivotally or otherwise connected to the staple or to the bridle, as may be desired, and is adapted to be swung into position between the staple and bridle, 110 so that in the operation of the device the bridle will be driven farther along the

frames 15 and 17 toward the rollers, by the effect of the filler 29 pushing against the bridle 22, when the handle 11 is pushed from the position shown in Fig. 4 to that shown in Fig. 1, thus pressing the rollers more tightly together and enabling the cloth to be wrung much drier or a very thin cloth to be wrung satisfactorily.

The operation of the device is extremely simple. The mop is shown in Fig. 1 in its operative form. When desired to wring out water from the cloth 13, the operator grasps the ferrule 14 in one hand and the handle 11 in the other, and draws back the handle, so that the cloth is drawn between the rollers and the water expelled therefrom. During this withdrawal of the handle, the bridle holds the rollers together, and the handle slips through the ring 24, while the staple 25 of the handle slides back along the rod 23 until when the wringing operation is practically complete, the parts are in the position shown in Fig. 3. A slight continued movement draws the cloth entirely through the rollers, and at the same time, the staple 25 engages the ring 24 and commences to draw back on the rod 23, thus retracting the bridle and permitting the jaw member 17 to drop, as shown in Fig. 4. The rollers are thus separated for re-introduction of the dry mop cloth, which is effected by merely reversing the movement of the handle, that is to say, pressing the same forward through the ferrule to carry the mop cloth between the separated rollers. The staple 25 travels the entire length of the rod 23 before engaging the bridle, and thus gives ample time for the introduction of the cloth between the rollers. When the staple engages the bridle, it carries the same along, and gradually closes the jaws to the position shown in Fig. 1.

From the foregoing description, it will be readily seen that the mop cloth may be wrung dry without ever touching the same with the hands, and that when all the mop

cloth has been wrung and is clear of the rollers, the same are automatically separated for the re-introduction of the cloth therebetween, and that after such re-introduction, the rollers are automatically closed without the necessity of manipulating any special devices.

Having thus described my invention, what I claim is:—

1. In a mop, a handle, a mop cloth carried thereby, a frame slidable on the handle having relatively movable jaws, rollers carried by the jaws arranged to press upon the mop cloth, a bridle normally holding the jaws closed, and means carried by the handle arranged to automatically operate said bridle back and forth.

2. In a mop, a handle, a mop cloth carried thereby, a frame slidably mounted on the handle, a jaw pivotally mounted on said frame, rollers mounted one on the jaw and one on the frame positioned to grasp the cloth between them, a bridle slidably mounted on the frame holding the jaw in closed position, and means carried by the handle for operating said bridle to release the jaw after the mop has passed between the rollers.

3. In a mop, a handle, a mop cloth carried thereby, a frame slidably mounted on the handle, a jaw pivotally mounted on the frame, rollers carried by said frame and jaw positioned to engage the mop cloth, a bridle embracing said frame and jaw and holding the rollers together, a rod connected to said bridle having a looped end traveling on the handle, and a staple on the handle embracing said rod and movable back and forth with the handle to alternately engage the loop and bridle.

In witness whereof, I have hereunto set my hand, in the presence of two witnesses.

FRANK L. CUNNINGHAM.
